(57) **CLAIM**

The ornamental design for a replacement tubing with connectors adapted for use in anal irrigation system, as shown and described.

DESCRIPTION

FIG. 1 is a perspective view of the replacement tubing with connectors adapted for use in anal irrigation system;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a perspective view thereof with the replacement tubing with connectors adapted for use in anal irrigation system.
The broken line showing parts of the drawings is included for the purpose of illustrating use and environment and forms no part of the claimed design.

1 Claim, 7 Drawing Sheets
